UNITED STATES PATENT OFFICE.

ANDREW C. BATCHELLER, OF BAY CITY, MICHIGAN.

HOOP-NAILING MACHINE.

SPECIFICATION forming part of Letters Patent No. 295,516, dated March 25, 1884.

Application filed January 18, 1884. (No model.)

To all whom it may concern:

Be it known that I, ANDREW C. BATCHELLER, a citizen of the United States, residing in Bay City, in the county of Bay 5 and State of Michigan, have invented a new and useful Hoop-Nailing Form, of which the following is a specification.

My invention relates to an improved method of manufacturing barrels by having a form corresponding in circumference to the circumference of the barrel upon which the hoops are designed to be driven, and the hoop being adjusted closely around the form with a proper portion of the ends overlapping each other, it 15 is quickly and securely fastened by nailing the overlapping ends together, and on being slipped off the form is ready to be driven upon the barrel; and the object of my improvement is to reduce the labor of manufacturing 20 barrels by providing a form which may easily be adjusted to conform to the size of different barrels, and I attain this object by the mechanism illustrated in the accompanying drawings, in which—

25 Figure 1 shows a vertical section of my improved hoop-former. Fig. 2 shows a transverse section of the same at the dotted line *xx*.

Similar letters refer to similar parts in all the views.

30 *a* and *b* represent two parts of a circular form, the circumference of which, when the parts are connected together, is about or nearly the same as that of an ordinary barrel. These parts *a* and *b* of the form are united together 35 at *f* and *h* by the bolts *c*. A portion at one end of this bolt *c* is provided with a right-hand thread and a portion of the opposite end with a left-hand thread, while between the threads and midway between the ends of the bolt *c*, 40 and rigidly attached thereto, is the nut *d*, and the parts *a* and *b* of the form are provided with a suitable thread to engage with that on the bolts *c*. So that when the bolts *c* are in position to connect the parts *a* and *b* together,

as shown in Fig. 1, by turning the bolts *c* in one 45 direction the circumference of the form is enlarged, and by turning the bolts *c* in the opposite direction the circumference of the form is diminished, and by this means an accurate adjustment of the form is obtained to conform 50 to the exact size of the barrel to be hooped, and as the size of the barrels manufactured is often changed, a corresponding change is quickly and easily made in the size of the form 55 as shown.

The usual manner of nailing the hoop is to place the hoop around the barrel somewhat above the position it is designed to occupy, and overlapping the ends and holding them together by the hands; it is raised off the barrel and placed on a suitable solid piece or anvil, and nails or staples are driven into the overlapping parts, and the hoop is then placed on the barrel and driven down to its proper position. Much of this labor is avoided by 65 the use of my improved form, as when the form is adjusted the hoop is placed thereon, and the overlapping parts nailed together. It is then placed on the barrel and driven down to its proper position.

Having fully described my improvement, what I claim as new, and desire to secure by Letters Patent, is—

In a hoop-nailing machine, a circular form consisting of the semicircular parts *a* and *b*, 75 joined together at their ends, as described, by the bolts *c*, which are provided in their centers by the rigid nuts *d*, and at one end a right-hand thread, and at the opposite end a left-hand thread, and adapted to engage with corresponding threads in the ends of the parts *a* and *b*, all in combination, substantially as set forth.

ANDREW C. BATCHELLER.
